No. 694,207.

Patented Feb. 25, 1902.

F. M. SMITH.
BRAKE MECHANISM.

(Application filed Nov. 6, 1901.)

(No Model.)

UNITED STATES PATENT OFFICE.

FINLEY M. SMITH, OF SALUBRIA, IDAHO.

BRAKE MECHANISM.

SPECIFICATION forming part of Letters Patent No. 694,207, dated February 25, 1902.

Application filed November 6, 1901. Serial No. 81,343. (No model.)

To all whom it may concern:

Be it known that I, FINLEY M. SMITH, a citizen of the United States, and a resident of Salubria, in the county of Washington and 5 State of Idaho, have invented certain new and useful Improvements in Brake Mechanism, of which the following is a specification.

The object of this invention is to provide a simple and effective brake for stopping the 10 momentum of a car by the application of brake-shoes directly to the track-rails, the said rail-brake to be used in conjunction with the ordinary air-brake mechanism and operated by the brake-cylinder thereof.

15 With the above object in view the invention consists of a bracket bolted to the under side of the car-body, a standard slidably vertically in said bracket and having a footpiece at its lower end carrying a shoe which 20 engages the rail, a bar or lever for moving the standard, and a cam for actuating said bar or lever, combined with chains connected to the ends of the shoe and to springs, which are adapted to hold the parts normally out of 25 operative position.

The invention further consists in the particular construction and combination of parts, all as will be hereinafter fully described, and specifically set forth in the appended claims.

30 In the accompanying drawings, which form a part of this specification, Figure 1 is a side elevation showing the application of my invention. Fig. 2 is a bottom plan view. Fig. 3 is a vertical sectional view on the line 3 35 of Fig. 2. Fig. 4 is an enlarged detail view.

Referring to said drawings, the letter A designates a bracket which is bolted to the under side of the car-body, at one side thereof, so as to be located over one of the track-rails, and this bracket is provided with a cylindrical socket B, in which is adapted to slide a vertical standard C, carrying the brake-shoe hereinafter described. To the lower end of this standard is connected a footpiece D, which extends longitudinally of the car and is firmly braced to said standard by arms or brace-rods c c, attached at their inner ends to a collar c', mounted on the standard. On the under side of the footpiece D is attached 45 a cast-iron shoe D', which engages the rail and receives the wear. It will be noted that this shoe is removable, so that when it be-

comes worn to any great extent it may be removed and a new one substituted. Though I have referred to this shoe as being made of 55 cast metal, it will be understood that any other material or a composite shoe may be used. To the ends of the shoe are attached chains E E, which extend in opposite directions from said shoe and are connected to rods e, slidably mounted in cylinders F, containing helical springs f, said springs being adapted to draw upon the chains, and thereby lift the brake-shoe out of operative position. The mechanism hereinafter described for applying 60 the brakes operates in opposition to these springs. The springs encircle the rods and are interposed between one end of the cylinder and an adjustable collar e' on said rods. The rods are also provided with an adjustable collar e² to prevent excessive movement 65 of the shoe in either direction, and thereby relieve the standard which carries the shoe.

H designates the operating-lever, which is provided at one end with gudgeons h h, by 70 which it is pivoted in the bracket A, the said lever passing through openings or slots b and c² in the socket and standard, respectively, and is engaged at its other end by a cam I, having an arm i, operated by the piston-rod 80 m of the brake-cylinder M. This brake-cylinder is of the ordinary type usually employed in connection with air-brakes, and the piston-rod m is connected to a lever N for operating the wheel-brakes. The brake-cylinder is connected to a train-pipe in the usual manner, and the operation of the brake mechanism hereinbefore described is controlled in 85 the same manner as an ordinary air-brake, either from the engine of a steam-railway 90 train or the front platform of a street-railway car. In case the mechanism is applied to a street-railway car any style of momentum-pump may be employed to produce the necessary air-pressure for operating the brake-cylinder. The piston-rod of the brake-cylinder is preferably provided with a spring n, as 95 shown, to first apply the wheel-brakes and then the track-brake upon a further movement of the piston-rod. The rod works through a casting n' on the lever N, and the tension of 100 the spring is adjusted by the collar m'.

From the foregoing description, in connection with the accompanying drawings, the

construction and operation of my improved 55
brake mechanism for cars will be readily un-
derstood, for in applying the rail-brake air
under pressure is admitted to the brake-cyl-
inder M, and the movement of the piston will
first operate the lever N to apply the wheel-
brakes and upon a further movement will
actuate the cam I, and said cam will depress
the lever H and force the standard C down-
ward, causing the brake-shoe D' to engage
the upper surface of the rail and by frictional
contact therewith quickly and effectively stop
the momentum of the car. The pressure of
the brake-shoe upon the rail is regulated by
the air-pressure in the brake-cylinder, and the
air-pressure is controlled in the usual man-
ner. The brake is quickly released by ex-
hausting the air-pressure in the brake-cylin-
der. The lever H being released and reliev-
ing the pressure upon the standard C permits
said standard to be raised by the springs f
lifting the brake-shoe a suitable distance
above the surface of the rail.

Though I have shown and described a sin-
gle set of rail-brake mechanism disposed at
one side of the car, it will be understood that
a similar set may be also located at the other
side, so that brakes could be applied to both
rails, and in practice a double set will be em-
ployed, especially when the brake mechanism
is applied to railway-cars.

Stopping the momentum of railway-cars by
the application of brake-shoes directly upon
the rails will not only more quickly and ef-
fectively bring the car to a standstill, but
will also relieve the wheel-brakes and reduce
the wear caused by contact of the brake-shoes
thereon. When wheel-brakes alone are used,
flat places are often worn on the periphery
40 of the wheel, producing a constant jolting of
the car as the wheel passes over the rail.
These objections are removed by applying
the brake-shoes directly to the rails in con-
junction with the regular wheel-brakes, and
45 the construction herein shown and described
performs the operation in a simple and effect-
ive manner, and the parts are so constructed
and arranged that they are not liable to get
out of order, can be readily adjusted, and are
50 strong and durable.

Having now described my invention, I do
not wish to be limited in my protection to
what is herein particularly shown and de-
scribed, for it is apparent that immaterial

changes or modifications may be made with-
out sacrificing any of the advantages of the
invention.

What I claim as new, and desire to secure
by Letters Patent, is—

1. In a railway-brake, the combination, of a 60
bracket having a socket, a standard slidable
in the socket and provided with a footpiece
at its lower end, a removable shoe attached to
the under side of the footpiece, and chains
connected to the ends of the shoe to reinforce 65
the standard; together with a lever pivoted
at one end and extending through the socket
and standard, a cam bearing upon the outer
end of the lever, and a brake-cylinder con-
nected to the cam, substantially as shown and 70
for the purpose set forth.

2. In a railway-brake, the combination, of a
bracket secured to the under side of the car
and having a socket B, a standard C slidable
in the socket and provided with a footpiece 75
at its lower end, a removable shoe attached to
the under side of the footpiece, chains at-
tached to the ends of the shoes and to rods
slidable in tubes on the under side of the car,
springs acting upon the rods to draw upon the 80
chains and lift the brake-shoe out of opera-
tion, and stops for limiting the movement of
the rods; together with a lever pivoted at one
end in the bracket and extending through
openings in the socket and standard, respec- 85
tively, a cam engaging the outer end of the
lever and provided with an arm, and a brake-
cylinder connected to the arm of the cam,
substantially as shown and for the purpose
set forth.

3. In a railway-brake, the combination with
the brake-cylinder M and lever N which op-
erate the wheel-brakes, of the piston-rod m
slidable in a casting on the lever N, a collar
or stop adjustable upon the piston-rod, and a 95
spring interposed between said stop and the
casting; together with a bracket, a standard
slidable vertically therein, a lever for depre-
ssing the standard, a cam operating said lever,
and a chain connecting the cam to the piston- 100
rod, substantially as shown and for the pur-
pose set forth.

In testimony whereof I affix my signature
in the presence of two witnesses.

FINLEY M. SMITH.
